Boston Type Foundry, No. 104 Milk Street, Boston.

UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,899, dated April 18, 1882.

Application filed March 16, 1882. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification.

The types composing this font consist of an alphabet of condensed Roman capitals, with figures and points, the letters and figures being ornamented with one or more points ex-

tending to the right and left about midway between the top and bottom of each, as shown in the accompanying impression taken from the types themselves, and showing exactly their form and outline.

I claim—

The design for types, as described and shown.

JOHN K. ROGERS.
